UNITED STATES PATENT OFFICE.

JEREMIAH P. JOHNSON, OF DETROIT, MICHIGAN.

DESIGN FOR A BRACE-BAR FOR CARRIAGE-BODIES.

SPECIFICATION forming part of Design No. 33,644, dated December 4, 1900.

Application filed October 22, 1900. Serial No. 33,976. Term of patent 7 years.

To all whom it may concern:

Be it known that I, JEREMIAH P. JOHNSON, a citizen of the United States, residing at Detroit, in the county of Wayne and State 5 of Michigan, have invented and produced a certain new and original Design for a Brace-Bar for Carriage-Bodies, of which the following is a specification, reference being had therein to the accompanying drawings, in 10 which—

Figure 1 is a perspective view, and Fig. 2 is a perspective view taken from a different point of view.

A is an angle-bar.

15 B and C are two channeled arms projecting laterally from one end of the bar A and perpendicular thereto and to each other.

The opposite end of the bar A terminates in the bifurcation D.

The leading feature of the design consists 20 in an angle-bar having two channeled arms projecting laterally from one end thereof and substantially perpendicular thereto and to each other.

What I claim as my invention is— 25

The design for a brace-bar for carriage-bodies, substantially as herein shown and described.

In testimony whereof I affix my signature in presence of two witnesses.

JEREMIAH P. JOHNSON.

Witnesses:

L. J. WHITTEMORE,
H. C. SMITH.
